Primary Examiner — Freda S Nunn(74) *Attorney, Agent, or Firm* — Banner & Witcoff, Ltd.(57) **CLAIM**

The ornamental design for a jug, as shown and described.

DESCRIPTION

FIG. 1 is a top, front, left perspective view of a jug showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The short-dash-long-dash broken lines shown immediately adjacent to the shaded areas represent the bounds of the claimed design. While the pairs of adjacent, spaced, jagged, broken lines are shown broken away to disclose indeterminate length, and the portions of the design that may be visible between the jagged lines have been removed for clarity. Further, the dash-dash broken lines are directed to environment only; none of the broken lines form a part of the claimed design.
